UNITED STATES PATENT OFFICE

FELIX RIESENBERG, OF TUCKAHOE, NEW YORK

CORDAGE STRUCTURE.

Application filed April 24, 1923. Serial No. 634,328.

To all whom it may concern:

Be it known that I, FELIX RIESENBERG, a citizen of the United States, and a resident of Tuckahoe, in the county of Westchester and State of New York, have invented a new and Improved Cordage Structure, of which the following is a full, clear, and exact description.

The present invention relates to new and useful improvements in cordage, and it pertains more particularly to a new and novel construction of cover for strands.

It is one of the objects of the present invention to provide a cover for strands in which the cover will withstand greater wear than covers as commonly constructed.

It is a further object of the invention to construct the cover so that the fibers from which it is formed, will occupy a position in which their longitudinal axis will be more nearly parallel to the longitudinal axis of the finished rope than is the case in rope as ordinarily constructed.

It is a further object of the invention to construct the cover so that a shorter length of individual fiber is presented to the abrasive action of wear in service, thereby increasing the life of the rope.

It is a still further object of the invention to construct the cover so that a better hold or grip may be obtained, which greatly enhances the value of the rope as a hand rope, such, for example, as hawsers, heavy sheet ropes, &c.

With the above and other objects in view, reference is had to the accompanying drawings, in which—

Figure 1 is a view in elevation of a rope constructed in accordance with the present invention, one of the strands of the rope being partially unraveled, and

Fig. 2 is a transverse sectional view taken on the line 2—2 of Fig. 1.

In the usual manner of making rope, the strands are formed from a number of yarns all of the same kind, that is, yarns spun from fiber. Several of these yarns are placed together to form the body of the rope, after which an outer layer of yarns is employed, the yarns of which outer layer consists are known as "cover yarns." These cover yarns in the usual method of manufacturing rope, are generally of the same size, shape, material and construction as the yarns employed in the body of the strand, and are laid spirally about the body of the strand

in such a manner as to provide a complete jacket therefor.

In carrying out the present invention, however, the yarns which are employed as "cover yarns" are of multiple ply, that is, two or more spun yarns twisted or laid together to form a cover element. A plurality of these cover elements are then spirally laid about the body of the strand to provide a complete cover or jacket therefor.

In the drawings, the reference character 5 designates the rope, and such rope is composed of strands 6 laid together. Each of these strands comprises a body portion 7, about which is spirally laid cover elements 8. As more clearly shown, each of these cover elements 8 comprises two yarns 9, which are twisted about each other or laid as heretofore described. By this construction it will be seen that the fibers of the yarns comprising the cover elements occupy a position substantially parallel to the longitudinal axis of the finished rope and that due to laying a plurality of yarns together to form a single cover element, a relatively short length of fiber is presented to the action of wear during usage of the rope.

While in the present instance the body of the strands is shown as comprising two members laid together, it is to be understood that the body of the strands may be a plurality of members either in twisted or untwisted relation without departing from the spirit of the invention, and, therefore, I do not wish to be limited to the two-part body construction shown in the drawings.

What is claimed is:

A rope comprising a plurality of strands twisted together in one and the same direction, each strand comprising a core of elements twisted together in a twist opposite to the twist of said strands, and a covering for each core, said covering comprising elements twisted together in a twist similar to the twist of the elements of said core, the elements of each core constituted of fibers twisted together in a twist opposite to the twist of the elements of the core, the elements of the covering constituted of yarns twisted together in a twist opposite to the twist of the elements of said covering, and said yarns constituted of fibers twisted together in a twist opposite to the twist of said yarns.

FELIX RIESENBERG.
